UNITED STATES PATENT OFFICE

2,213,982

METALLURGIC WEIGHING APPARATUS

Albert A. Frey, Forest Hills, and Edward J. Parsons, Vandergrift, Pa.

Application April 23, 1938, Serial No. 203,922

1 Claim. (Cl. 265—27)

This invention relates to metallurgy, one of the objects being to enable the production of an alloy or modified metal having a more exactly determinable chemical analysis than is af-
5 forded by the prior art teachings.

A specific example of the invention is illus-
trated by the accompanying drawing, in which:

Figure 1 is a side view; and,
0 Figure 2 is a cross-sectional elevation on line II—II of Figure 1.

More specifically, the drawing shows a con-
ventional molten steel ladle 1 with its rests 2
resting on the centers of parallel structural
5 beams 3 whose ends are supported from the
floor by short columns 4 and which are cen-
trally provided with fixedly positioned lugs 5
embracing and centering the rests 2. A pit 6 is
formed in the floor supporting the columns 4 to
provide room for the ladle 1 and to permit the
use of columns of conveniently restricted lengths.

Since the ladle is mounted by the tops of the
beams 3, the bottoms of the latter are placed
under tension by the weight of the ladle, and this
tension is transmitted to a rod 7 fixed parallel
to the bottom of one of the beams 3 in spaced
relationship by means of lugs 8 welded to the
bottom of the beam and to the rod 7, these lugs
8 being equally spaced to either side of the cen-
ter of the beam.

It follows that the rod 7 is strained various
amounts when stressed various amounts by flex-
ing of the beam, resulting from the weight of
the ladle 1, which varies according to the weight
of steel or other metal which it contains. The
operating element 9 of an electro-magnetic
strain indicator is fixed to this rod 7, this ele-
ment being powered through wires 10 and con-
nected by wires 11 to a milliammeter 12 cali-
brated to read in units of weight. Strain gauges
of this type are commercially available.

The apparatus described may be used for the
purpose of producing alloy steel. Thus, molten

steel to be alloyed can be poured into the ladle
1 and its exact weight determined by obser-
vation of the milliammeter 12, it being under-
stood that the weight of the ladle 1 must be de-
ducted from the total reading obtained. This
information permits the calculation of the ex-
act weight of alloying substance which must be
added to the steel in the ladle to produce an
alloy of the desired chemical analysis, due re-
gard being given to vaporization losses and the
like.

The addition of an amount of the alloying sub-
stance to the molten steel in the ladle 1, which
is proportioned in weight to the weight of the
steel to produce an alloy of the desired chemical
analysis, completes the process. Since the ad-
ditions are made by weight instead of the usual
method of indirect determination by observa-
tion of the volume of steel in a ladle, a very
exactly proportioned alloy results.

We claim:

A molten metal weighing apparatus comprising
the combination of a molten metal ladle,
a beam fixed at spaced positions against down-
ward movement and mounting said ladle be-
tween said positions so as to flex downwardly
in a curve between said positions under the
weight of said ladle, whereby the lower portion
of said beam is placed in tension, a rod extend-
ing along said lower portion of said beam and
rigidly fixed to the latter on either side of the
position where it mounts said ladle so that said
rod is also placed in tension so as to strain,
and a strain gauge worked by said rod, where-
by the degree said rod is strained by tension
received from said lower portion of said beam
resulting from said beam flexing under the
weight of said ladle may be used to determine
the weight of said ladle by appropriate calibra-
tion of said strain gauge.
